U.S. Appl. No. 29/387,947, Tinius.

* cited by examiner

Primary Examiner — Austin Murphy(74) *Attorney, Agent, or Firm* — McGuireWoods LLP(57) **CLAIM**

I claim the ornamental design for a chainsaw, as shown and described.

DESCRIPTION

FIG. 1 is a right-rear perspective view of the chainsaw; FIG. 2 is a front view of the chainsaw shown in FIG. 1; FIG. 3 is a rear view of the chainsaw shown in FIG. 1; FIG. 4 is a right side view of the chainsaw shown in FIG. 1; FIG. 5 is a left side view of the chainsaw shown in FIG. 1; FIG. 6 is a top view of the chainsaw shown in FIG. 1; and, FIG. 7 is a bottom view of the chainsaw shown in FIG. 1. The broken lines shown in the drawings represent portions of the chainsaw that form no part of the claimed design. The subject matter shown in dashed lines, and any surfaces of the design not shown, including interior surfaces, form no part of the claimed invention.
